APPARATUS FOR THE CONTROL OF HIGHWAY CROSSING SIGNALS

Arthur E. Dodd and Henry S. Young, Wilkinsburg, Pa., assignors to The Union Switch & Signal Company, Swissvale, Pa., a corporation of Pennsylvania

Application July 28, 1936, Serial No. 93,028

15 Claims. (Cl. 246—130)

Our invention relates to apparatus for the control of highway crossing signals, and particularly to apparatus controlled by a train approaching a highway crossing for governing the operation of a highway crossing signal in accordance with the speed of the train.

A feature of our invention is the provision of novel and improved apparatus controlled by a train as it travels two or more consecutive track sections in approaching a highway crossing for initiating the operation of a highway crossing signal if the train exceeds a particular speed predetermined for each track section. Another feature of our invention is the provision of apparatus of the type here involved for preventing an accidental interruption of a circuit associated with a track section some distance in advance of a train having the effect of shortening the warning period of the highway crossing signal. Still another feature of our invention is the provision of apparatus of the type contemplated which is governed by track instruments. Other features and advantages of our invention will appear as the specification progresses.

We will describe two forms of apparatus embodying our invention, and will then point out the novel features thereof in claims.

Apparatus controlled by a train as it travels two or more consecutive track sections in approaching a fixed location to operate a time measuring means for establishing a signal control if the train exceeds the limit of speed predetermined for any track section, has been proposed in the United States application for Letters Patent Serial No. 61,561, filed January 30, 1936, by George W. Baughman, for Railway signaling apparatus. Our invention may be considered an improvement on the Baughman application.

In the accompanying drawings, Fig. 1 is a diagrammatic view of one form of apparatus embodying our invention, and wherewith the apparatus is governed by a train through the medium of track circuits of insulated track sections. Fig. 2 is a diagrammatic view of a second form of apparatus embodying our invention, and wherewith the apparatus is governed by a train through the medium of track instruments placed at selected points, the railway track being thus formed into track sections the limits of which are defined by the locations of the track instruments.

In each of the different views, like reference characters designate similar parts.

Referring to Fig. 1, the reference characters

1a and *1b* designate the track rails of a stretch of railway over which traffic normally moves in the direction indicated by an arrow, and which track rails are intersected by a highway *H*. The track rails *1a* and *1b* are formed by the usual insulated rail joints into four track sections *1T*, *2T*, *3T*, and *4T* which a train travels successively in the order named in approaching the highway *H* when it is traveling in the normal direction of traffic. These track sections are each provided with a track circuit consisting of a source of current such as a battery *2* connected across the rails at one end of the section and a track relay indicated by the reference character *R* plus a prefix corresponding to the section connected across the rails at the other end of the section. It is to be observed that the track relays *1TR*, *2TR*, *3TR* and *4TR* associated with the insulated track sections *1T*, *2T*, *3T* and *4T*, respectively, are traffic controlled relays which are normally energized and which become de-energized in response to a train entering the associated track section. A repeater relay *2TPR* is controlled over a front contact *20* of the track relay *2TR*. As will appear hereinafter, the respective lengths of these several track sections hold a definite relationship with respect to each other, and which relationship is dependent upon the desired warning period of the highway crossing signal prior to the arrival of a train at the intersection, and also upon the minimum and maximum speeds of the trains passing over the intersection. The track section *1T* is a time measuring section, section *2T* is a combined time measuring and signal operating section, and sections *3T* and *4T* are operating sections. The length of each section *1T* and *2T* is directly proportional to a speed limit predetermined for the section, and they bear a selected relation as to the distance between the highway crossing and the near end of the section. This distance is such that in each case substantially the same interval of time is required for a train to move from the near end of the section to the highway crossing at the respective predetermined speed limits. The function of such selected lengths for the several track sections will be described more fully hereinafter.

Two highway crossing signals *S1* and *S2* are located adjacent the intersection and are here shown as flashing light highway crossing signals. In accordance with standard practice, these two signals are set for one to be exhibited to highway traffic approaching the crossing in one direction and the other signal to be exhibited to high-

way traffic approaching the crossing in the opposite direction. The signal S2 is also provided with an audible indication in the form of an electric bell EB. It will be understood, of course, that our invention is not limited to this specific form of highway crossing signal, and other forms such as wigwags, gates, or barriers may be used if desired.

The immediate control of signals S1 and S2 is effected by a flasher relay FR and an interlocking relay XR. The flasher relay FR may be any one of several types which are well-known to the art. It is deemed sufficient for this application to point out that when relay FR is deenergized, its two contact fingers 6 and 7 are biased to a mid position, that is, to the position illustrated in the drawings, but that when the relay is energized, these contact fingers are oscillated between two extreme positions which are indicated on the drawings by dotted lines, the rate of oscillation being, say, for example, 30 cycles per minute. Contact finger 6 in its mid position makes engagement with two mating contacts 8 and 9, but when swung to its left-hand position, it breaks engagement with contact 8, and when swung to its right-hand position, it breaks engagement with contact 9. Likewise, contact finger 7 in its mid position makes engagement with two mating contacts 10 and 11, and breaks engagement with the contacts 10 and 11 in the left-hand and right-hand positions, respectively.

Relay XR is preferably a standard type interlocking relay. The winding 3 of relay XR is controlled by the apparatus associated with the track sections to the left of the highway H in a manner to be explained later. The winding 19 of relay XR may be governed in the usual manner by apparatus responsive to traffic approaching the highway H from the right but which apparatus is not shown in the drawings since it forms no part of our invention. When winding 3 of relay XR is deenergized and its back contacts 4 and 13 are closed, current is supplied to the operating winding of relay FR and to the signals S1 and S2. The closing of back contact 4 of relay XR completes a circuit extending from the B terminal of any convenient source of current such as a battery not shown over back contact 4, wire 5, winding of relay FR, and to the C terminal of the current source, and relay FR is set into operation. A branch circuit extends from wire 5 over wire 12, operating winding of bell EB and to the C battery terminal, and the bell sounds an alarm. The closing of back contact 13 of relay XR completes operating circuits extending from the BX terminal of a source of current such as a line transformer, not shown, over back contact 13, wire 14, contact fingers 6 and 7 of relay FR, thence to the lamps 15 and 16 of signal S1, and to the lamps 17 and 18 of signal S2, and to the CX terminal of the current source, as will be readily understood by an inspection of Fig. 1. It follows that signals S1 and S2 are normally dark and the bell EB is silent, but that release of winding 3 of relay XR and the closing of contacts 4 and 13, causes the bell EB to sound an alarm, and the relay FR to be operated and the lamps of each of the signals S1 and S2 to be alternately flashed. It is to be noted that should relay FR fail to operate, the lamps of the signals S1 and S2 are continuously illuminated.

The control apparatus located at the intersection also includes a time measuring means which may take different forms, and which, as here shown, consists of three associated relays SR,

TR, and TPSR. Relay SR is a direct current neutral relay which functions as a control relay for the other two relays TR and TPSR. Relay TR is a slow acting relay having slow to pick up characteristics, and relay TPSR is slow releasing in character. The slow acting relay TR may be of the type described in the United States Letters Patent No. 1,966,965, granted July 17, 1934, to Branko Lazich and H. E. Ashworth for Electrical relays. Relay TR is so proportioned and adjusted that its contact arm 27 is moved and makes engagement with a front contact 26 only after the winding of the relay has been energized a predetermined period say, for example, 15 seconds; but that upon deenergization of the winding of the relay, contact arm 27 immediately drops from whatever position it has advanced back to its normal position. A contact finger 28 is operatively connected with the contact arm 27 as indicated by a dotted line in the drawing, to check the normal position of arm 27, the arrangement being such that contact finger 28 engages a stationary contact 29 only when the contact arm 27 occupies its full normal position. As will shortly appear, the relays of the time measuring means are successively operated as a train travels the sections 1T and 2T.

Normally, that is to say, when the track sections are all unoccupied, the track relays are each energized by virtue of the track circuit in which each is included, and the winding 3 of relay XR is energized over a circuit which may be traced from the B battery terminal over front contact 30 of track relay 2TR, front contact 31 of repeater relay 2TPR, front contact 32 of track relay 3TR, front contact 33 of relay 4TR, winding 3, and to the C terminal of the current source. The relays SR, TR, and TPSR of the time measuring means, as well as a relay 3SR to be referred to later, are normally deenergized.

In describing the operation of the apparatus of Fig. 1, we shall assume a permissible variation in the warning period of signals S1 and S2 prior to arrival of a train at the highway of 20 to 33 seconds, and that the train speeds are between a minimum speed of 25 miles per hour and a maximum speed of 80 miles per hour. To agree with this permissible variation in the warning period, the operating time of the slow acting relay TR is preferably 15 seconds. On the above assumptions, the track sections 1T, 2T, 3T, and 4T are preferably 1170, 686, 520, and 1144 feet in length, respectively.

We shall first consider the operations that take place in response to a train moving through the track sections at the assumed minimum speed of 25 miles per hour, or 36.6 feet per second. The train, upon entering section 1T, shunts track relay 1TR, and that relay, upon releasing, completes at its back contact 34 an energizing circuit for the control relay SR of the time measuring means, and relay SR is picked up. This circuit includes battery terminal B, back contact 34 of relay 1TR, wire 35, back contact 36 of relay 3SR, front contact 37 of relay 2TPR, front contacts 38, 39, and 40 of relays 2TR, 3TR, and 4TR, respectively, check contact 28-29 of relay TR, winding of relay SR, and the C terminal of the same source of current. The control relay SR on picking up completes at its front contact 41 a shunt path around the check contact 28-29, and completes at its front contact 42 a simple operating circuit for the slow acting relay TR. Relay TR requires 15 seconds' operating time to close its contact 26-27, and hence when the train has

advanced approximately 550 feet in section 1T, which is 1170 feet in length, the relay TR picks up and completes a pick-up circuit for relay TPSR, this pick-up circuit including a front contact 43 of relay SR as well as the contact 26-27 of the slow acting relay TR. Relay TPSR at once picks up and closes its front contacts 44 and 45. The closing of front contact 44 prepares a stick circuit network by which relay TPSR is subsequently retained energized. This stick circuit network may be traced from B battery terminal over front contact 46 of repeater relay 2TPR, back contact 47 of track relay 2TR, front contact 48 of relay 3TR, front contact 49 of relay 4TR, front contact 44 and winding of relay TPSR, and to the C battery terminal. A branch path for this circuit network extends from the B battery terminal over front contact 50 of relay 3SR, back contact 51 of relay 3TR, and thence as previously traced. It is to be noted that with relays SR and TPSR picked up and their respective front contacts 52 and 45 closed, the winding 3 of relay XR is provided with two branch paths in multiple over either one of which it may receive current, front contact 33 of relay 4TR being also included in these branch paths.

When this train advances and enters section 2T, the track relay 2TR is shunted and is released. The repeater relay 2TPR is now deenergized and releases at the end of its slow release period. The circuit for control relay SR is now open at front contact 38 of relay 2TR and relay SR is released and in turn deenergizes relay TR which immediately drops its contact arm 27 to the normal position and recloses check contact 28-29. Release of relay SR also opens the pick-up circuit of relay TPSR but that relay is retained energized during the slow release period of relay 2TPR over the stick circuit which includes front contact 46 of relay 2TPR and back contact 47 of relay 2TR. At the expiration of the release period of relay 2TPR, relay 2TPR releases and opens this stick circuit for relay TPSR and the latter relay is deenergized and releases at the end of its slow release period. During the period relay TPSR is up and relay 2TPR is down, a second energizing circuit for control relay SR is formed and relay SR picks up to start a new operation of relay TR. This second circuit for relay SR includes B battery terminal, front contact 45 of relay TPSR, front contact 32 of relay 3TR, back contact 53 of relay 2TPR, back contact 54 of relay 2TR, front contacts 39 and 40 of relays 3TR and 4TR, respectively, check contact 28-29, winding of relay SR and the C terminal. Relay SR is retained energized over its own front contact 52 and the above traced second circuit subsequent to the release of relay TPSR. It is to be noted that the two slow release relays 2TPR and TPSR are released in sequence and the total slow release time of the two relays is available for effecting the operation of releasing relays SR and TR and reenergizing relay SR. We have found that relays 2TPR and TPSR when of the usual construction for slow release relays provide an interval sufficient to bridge the time required for relay TR to be reset and close its check contact, and the relay SR to be picked up, when the two slow release relays are released in sequence.

The normal energizing circuit of winding 3 of relay XR is opened at front contact 30 when relay 2TR is released in response to the train entering section 2T, but winding 3 is supplied with current over the branch path including front contact 45 of relay TPSR subsequent to the release of

relay 2TR, and then over the branch path including front contact 52 of relay SR subsequent to the release of relay TPSR. Furthermore, relays 2TR and 2TPR when released, close a pickup circuit for the relay 3SR, and that relay is energized and picks up at the end of a slow pickup period. This circuit includes B battery terminal, back contact 21 of relay 2TR, back contact 22 of relay 2TPR, front contact 23 of relay 3TR, winding of relay 3SR, and the C battery terminal. Operation of relay 3SR at this time, however, performs no useful function except to prepare the stick circuit for relay TPSR at front contact 50. It follows that entry of the train into the track section 2T is effective to cause the time measuring means to be reset to its normal position and a new operation thereof initiated, to transfer the control of winding 3 of relay XR from its normal or main energizing circuit, which is governed by the track circuits to its two branch paths which are controlled by relays SR and TPSR of the time measuring means, and to energize relay 3SR.

By the time the train traveling 25 miles per hour advances approximately 550 feet in section 2T, which is 686 feet in length, the relay TR is again operated to close its contact 26-27, and the relay TPSR is again picked up. When the train passes into section 3T, the track relay 3TR is shunted and is released. The opening of front contact 39 of track relay 3TR removes current 30 from the control relay SR and that relay is released, and, in turn, the slow acting relay TR is deenergized and is restored to its normal position. The relay TPSR is retained energized this time over its stick circuit which includes the front contact 50 of relay 3SR and back contact 51 of track relay 3TR, relay 3SR being held up over a stick circuit including back contact 24 of relay 3TR and its own front contact 25. Winding 3 of relay XR is energized subsequent to the release of relay SR over the branch path which includes front contact 45 of relay TPSR. Relays SR and TR are not again reenergized since the energizing circuit for relay SR remains open at front contact 39 of relay 3TR. Consequently, relay TPSR is held energized over its stick circuit during the time the train is advancing through the track section 3T.

When the train enters section 4T, track relay 4TR is shunted and releases to open its front contact 33 which is interposed in the branch paths as well as in the main circuit for the winding 3. With winding 3 deenergized and its back contacts 4 and 13 closed, operation of signals S1 and S2 is effected in the manner set forth hereinbefore. Relay TPSR is now deenergized and restored to its normal position since its stick circuit is open at the front contact 49 of the track relay 4TR. It follows that the warning period prior to the arrival of the train at the intersection is substantially 31 seconds since the track section 4T is 1144 feet in length and the train is operating at about 36.6 feet per second.

We shall assume next that a train approaches the highway H travelling at the maximum speed of 80 miles per hour or 117.3 feet per second. When the train enters section 1T and shunts track relay 1TR, that relay is released and closes at its back contact 34 the energizing circuit for control relay SR the same as described for the first train. With relay SR picked up the slow acting relay TR is energized to initiate its operation. Contact 26-27 of relay TR is not closed, however, prior to the train entering the track section 2T since this train consumes only about 10

seconds in advancing through the section $1T$, whereas the operating time for relay TR is 15 seconds. Consequently, relay $TPSR$ is not picked up prior to the shunting of the track relay $2TR$ with the result that when front contact 38 of track relay $2TR$ is opened and relay SR is deenergized, this relay remains deenergized inasmuch as its second energizing circuit which includes back contact 54 of relay $2TR$ is open at front contact 45 of the relay $TPSR$. Release of the track relay $2TR$ and the opening of its front contact 30 deenergizes the winding 3 of relay XR since the branch paths are now both open. Hence, operation of signals $S1$ and $S2$ is initiated when the train operating at the maximum speed of 80 miles per hour enters the track section $2T$. The warning period of signals $S1$ and $S2$ prior to the arrival of the train at the intersection is substantially 20 seconds since the total distance from the exit end of section $1T$ to the highway is 2350 feet.

It is apparent that for all trains exceeding the speed of 53.4 miles per hour or about 78.4 feet per second, in section $1T$, operation of the highway crossing signals is initiated in response to the train entering section $2T$ since all such trains reach the exit of section $1T$ in less than 15 seconds, the operating time of the slow acting relay TR . A train moving 53.4 miles per hour consumes substantially 30 seconds in advancing from the exit end of track section $1T$ to the highway. Thus for train speeds between 80 and 53.4 miles per hour the variation in the warning period of the highway crossing signal is within the assumed permissible variation.

If a train is operating at a speed slightly less than 53.4 miles per hour and consumes 15 seconds in traveling track section $1T$ and entering section $2T$, the slow acting relay TR is operated and relay $TPSR$ is picked up prior to the time the track relay $2TR$ is shunted. With relay $TPSR$ picked up, it is retained energized by virtue of its stick circuit which includes the back contact 47 of relay $2TR$ and the front contact 46 of the repeater relay $2TPR$, and a second operation of the time measuring means is effected in the manner described for the train operating at 25 miles per hour. Likewise, winding 3 of relay XR is retained energized over its branch paths including front contact 52 of relay SR and front contact 45 of relay $TPSR$ for such train speed.

If a train exceeds a speed of 31.2 miles per hour or 45.8 feet per second and consumes less than 15 seconds in operating over track section $2T$, the highway crossing signals are set into operation in response to the train entering the section $3T$, since the slow acting relay TR is not operated the second time to close its contact $26-27$ and cause the energization of relay $TPSR$ prior to the shunting of the track relay $3TR$. Under such circumstances, the release of track relay $3TR$ to open its front contact 39 causes relays SR and TR to be restored to their normal positions with the relay $TPSR$ deenergized, with the result the winding 3 is without current and releases to start the operation of the highway crossing signals. The total distance from the exit end of section $2T$ to the highway is 1664 feet, and hence the warning period of the highway crossing signals for a train operating a little above 31.2 miles per hour is approximately 33 seconds.

If the train is moving a little less than 31.2 miles per hour in section $2T$ and consumes something over 15 seconds in advancing therethrough,

and relay TR has completed its second operation and picked up relay $TPSR$ prior to the shunting of track relay $3TR$, the relay $TPSR$ is retained energized over its stick circuit including back contact 51 of relay $3TR$. Under these circumstances, winding 3 of relay XR is retained energized over its branch path including front contact 45 of relay $TPSR$.

It is to be seen, therefore, that for train speeds above 53.4 miles per hour, the predetermined speed for section $1T$, the signals $S1$ and $S2$ are set into operation in response to the train entering track section $2T$. The warning period prior to the arrival of the train at the crossing is in this case within the permissible variation of 20 to 33 seconds, since the distance between the highway and the near end of section $1T$ is such that a train operating at 53.4 miles per hour consumes substantially 30 seconds and a train operating at the maximum speed of 80 miles per hour consumes about 20 seconds in advancing therethrough. For train speeds between 53.4 and 31.2 miles, the predetermined speed for section $2T$, the highway crossing signals are set into operation in response to the train entering section $3T$. Again, the warning period is within the permissible variation, since the distance between the highway and the near end of section $2T$ is such that a train operating at 31.2 miles per hour consumes approximately 33 seconds and a train operating at a speed of a little less than 53.4 miles per hour consumes approximately 20 seconds in advancing therethrough. For train speeds between 31.2 miles per hour and the assumed minimum speed of 25 miles per hour, the operation of the highway crossing signals is delayed until the train enters the section $4T$ and a warning period of at least 20 seconds is effected, since the distance from the highway to the near end of section $3T$ is such that a train operating at the speed of 31.2 miles per hour consumes about 22 seconds in advancing therethrough.

It should be pointed out that for certain train speeds the pickup circuit for relay $TPSR$ is opened almost immediately after having been closed. The stick circuit for relay $TPSR$ assures that if this relay is once picked up by virtue of the slow acting relay TR having completed its operation, it remains energized although relay TR is reset almost immediately, such operation of relay TR occurring with certain train speeds. Consequently, full release period of relay $TPSR$ along with the release period of relay $2TPR$ for resetting the slow acting relay TR and reenergizing the control relay SR to initiate a new operation of relay TR under all conditions of train speeds are assured.

The slow pickup relay $3SR$ is provided so that an interruption of the track circuit for the section $3T$ will not complete the stick circuit for relay $TPSR$ of the time measuring means while the train is approaching in section $1T$ and the time measuring means is being reset as the train enters section $2T$. Relay $3SR$ is so proportioned that its slow pickup period is slightly greater than the time required for relay $TPSR$ to release. Assume a medium speed train, say 60 miles per hour, is traveling through track section $1T$ and relay TR has operated and picked up relay $TPSR$, and then the track circuit for section $3T$ is accidentally interrupted and track relay $3TR$ is released at the time the relays SR and TR are being reset. The relays SR and TR would be restored to their normal positions because the front contact 39 interposed in the energizing circuit of relay SR is

now open. The relay TPSR also would be released because its stick circuits are open at the front contact 50 of relay 3SR, and front contact 46 of relay 2TPR. Hence, operation of the highway crossing signals is initiated at once and their operation is continued until the train has advanced over the crossing. Were the relay 3SR not provided and the track circuit for section 3T accidentally interrupted under the conditions set forth above, the relay TPSR might be retained energized over its stick circuit including back contact 51 of relay 3TR and operation of the highway crossing signals might not be initiated for such medium speed trains until the train entered the final operating section 4T. However, with the apparatus constructed in the manner disclosed in Fig. 1 shortening of the warning period of the highway crossing signal in the case of a track circuit interruption at some distance in advance of a train is avoided.

It will be understood, of course, that our invention is not limited to the specific train speeds, variation in warning periods, and lengths of track sections assumed in describing the operation of the apparatus of Fig. 1, and a study of the invention will disclose the flexibility of the system.

In Fig. 2, the track rails 1a and 1b of a stretch of railway are arranged in a single insulated track section 5T, which is intersected by a highway H adjacent the exit end of the section. The track section 5T is provided with the usual track circuit including a track relay 5TR. Three track instruments R1, R2, and R3 are associated with the track rail 1b of the track section 5T, these track instruments being located at locations BT, CT and DT, respectively. These track instruments may be any one of several different types and are shown conventionally for the sake of simplicity since their specific structure forms no part of our invention. One form of track instrument that may be used is disclosed and claimed in a copending application for Letters Patent Serial No. 54,500, filed December 14, 1935, by H. G. Witmer, for Circuit controlling instruments. In this form of track instrument a circuit controlling contact is biased to a closed position and is operated to an open position by the vibration set up in the track rail by a train wheel passing over the point at which the instrument is attached to the rail. It will be understood, of course, that our invention is not limited to this one form of track instrument and other forms may be used. The significant point is that each track instrument is provided with a normally closed contact which is operated to an open position in response to the leading wheel of a train passing the location of that track instrument, and which contact is returned to its normal closed position subsequent to the train passing the location. Looking at track instrument R1, its contact 55-56 is normally closed and is operated to an open position in response to a train passing location BT, and is then returned to its closed position after the train has passed. Contacts 67-68 and 58-59 of track instruments R2 and R3, respectively, are operated in a similar manner.

The distances AT-BT, BT-CT, CT-DT, and DT-ET bear a relationship to each other similar to that described for the track sections 1T, 2T, 3T, and 4T of Fig. 1. That is to say, the stretch of railway of Fig. 2 is formed into four track sections the lengths of which are defined by the insulated section 5T and the locations of the track instruments. Hence, the section AT-BT constitutes a time measuring section, section

BT-CT a combined time measuring and operating section, and sections CT-DT and DT-ET operating sections in the same manner as the track sections of Fig. 1.

Each track instrument controls a relay designated by the reference character R plus a prefix to indicate the location of the track instrument. The control circuits for each of these relays are the same and it is thought that a description of the circuits for one will suffice for an understanding of all. Relay DR associated with track instrument R3 is provided with a pickup circuit which includes battery terminal B, front contact 57 of track relay 5TR, winding of relay DR, and the C battery terminal; and is also provided with a stick circuit which includes its own front contact 60 and the contact 58-59 of track instrument R3. Relay BR controlled by the track instrument R1 governs over its front contact 61 a slow release repeater relay BPR. It is to be observed that the relays BR, CR and DR associated with the track sections BT-CT, CT-DT and DT-ET, respectively, as well as the relay 5TR of track section 5T, are traffic controlled relays which are normally energized and which become deenergized in response to a train entering the associated track section.

The highway crossing signals S1 and S2 of Fig. 2 are governed by a flasher relay FR and an interlocking relay XR in the same manner as described in Fig. 1. Furthermore, the control apparatus includes a time measuring means which consists of three relays SR, TR, and TPSR the same as in Fig. 1.

In Fig. 2, certain of the contact fingers of the several relays are shown remote from the winding of the relay in order to simplify the drawings as much as possible. In each case the contact finger is given a reference character corresponding to the associated relay plus a distinctive numeral, and each such contact finger is illustrated in the position corresponding to the position of the relay.

To prevent an accidental interruption of the circuit for relay CR while a train is advancing through the first timing track section from shortening the warning period, a slow pickup relay BSR is provided. This relay BSR is controlled over a pickup circuit which includes back contacts 62 and 63 of relays BR and BPR, respectively, as well as a front contact CR64; and is then retained energized by a stick circuit which includes a back contact 65 of relay CR and its own front contact 66.

In describing the operation of the apparatus of Fig. 2, we shall assume that the maximum and minimum train speeds, and the permissible variation in the warning period are the same as assumed in Fig. 1. Hence, the preferred operating time for relay TR of the time measuring means is 15 seconds, and the track sections AT-BT, BT-CT, CT-DT, and DT-ET are 1170, 686, 520, and 1144 feet in length, respectively.

Taking the case of a train operating at the minimum speed of 25 miles per hour, the track relay 5TR is shunted and releases in response to the head end of the train passing the location AT. Release of relay 5TR opens the pickup circuit for each of the relays BR, CR, and DR, and these relays are retained energized over their stick circuits governed by the respective track instruments. Release of relay 5TR also closes back contact 5TR69 and completes an energizing circuit for control relay SR of the time measuring means. This circuit comprises the ele-

ments, battery terminal B, back contact 5TR69, front contact BPR70, front contact BR71, front contact CR72, front contact DR73, back contact BSR74, check contact 28-29, winding of relay 5SR, and C battery terminal. Relay SR picks up and closes at its front contact 41 a shunt path around the check contact 28-29 and contact BSR74, and completes at its front contact 42 the operating circuit for the relay TR. Prior to arrival of the train at location BT, relay TR completes its operation and picks up relay TPSR since the section AT-BT is 1170 feet and the train is operating at only 36.6 feet per second and requires something over 15 seconds in passing through that section. When the train arrives at location BT and operates the track instrument R1, the stick circuit for relay BR is opened and that relay is deenergized and releases to open front contact BR71 interposed in the energizing circuit of relay SR and relays SR and TR are reset to their normal positions. Repeater relay BPR is also deenergized in response to the release of relay BR and releases at the end of its slow release period. During the interval relay BPR is up and relay BR is down, relay TPSR is retained energized by its stick circuit which includes front contact BPR76 and back contact BR75 as will be understood by an inspection of Fig. 2. When relay BPR releases and opens front contact BPR76, the relay TPSR is deenergized and releases at the end of its slow release period, the two relays BPR and TPSR being thus released in sequence.

Release of the repeater relay BPR also opens front contact BPR78 and closes the corresponding back contact 79. The opening of front contact BPR78 discontinues the supply of current to winding 3 of relay XR over the normal energizing circuit of that winding, but winding 3 is supplied with current over its branch path which includes front contact 45 of relay TPSR and the front contact DR81. The closing of back contact 79 of relay BPR completes a second energizing circuit for the control relay SR and which circuit comprises the elements, B battery terminal, front contact 45, front contact CR71, back contact 79, back contact 80, front contact CR72, front contact DR73, back contact BSR74, check contact 28-29, winding of relay SR, and C battery terminal. Hence, relay SR is reenergized and picked up to close the shunt path around the check contacts 28-29 and BSR74, and to reenergize the slow acting relay TR to start a second operation of that relay. Subsequent to the release of relay TPSR, the winding 3 of relay XR is supplied with current over the branch path which includes front contact 52 of relay SR.

Relay TR completes its second operation and again picks up the relay TPSR prior to the arrival 60 of the train at location CT since the track section BT-CT is 680 feet in length and the train consumes something over 15 seconds in passing therethrough. When the train arrives at location CT and operates track instrument R2, the stick circuit for relay CR is opened and that relay is released and opens at its front contact CR71 the second energizing circuit for relay SR with the result that relays SR and TR are again restored to their normal positions. This time 65 relay TPSR is retained energized over a stick circuit which includes front contact BSR82 and back contact CR83, since the relay BSR is picked up during the interval the train is passing through the section BT-CT. With relay TPSR thus retained energized, winding 3 is supplied with cur-

rent during the time the train is advancing through the section CT-CT. When the train arrives at location DT and operates track instrument R3 the relay DR is deenergized and releases to open front contact DR81 interposed in the circuit for the winding 3. Hence, winding 3 is deenergized and operation of the highway crossing signals is initiated in response to the train entering the section DT-ET and a warning period of substantially 30 seconds prior to the arrival of the train at the intersection is effected. Release of relay DR also opens front contact DR84 interposed in the stick circuit for relay TPSR and that relay is restored to its normal position. When the train passes over the intersection and to the right of location ET, the relay 5TR is reenergized and the apparatus is restored to its normal position, that is, to the position illustrated in Fig. 2.

From the foregoing, it is apparent that the apparatus of Fig. 2 operates for a train traveling at the maximum speed of 80 miles per hour and for all train speeds between the maximum and minimum speed in a manner similar to the apparatus of Fig. 1 and it is thought that the operation need not be repeated in detail. Suffice it to say, for train speeds between 53.4 and 80 miles per hour, operation of the highway crossing signals is started when the train enters section BT-CT and operates the track instrument R1. For train speeds between 31.2 and 53.4 miles per hour, operation of the highway crossing signals is started when the train enters section CT-CT and operates track instrument R2. For train speeds between 31.2 and the minimum speed of 25 miles, the signals are set into operation when the train enters the section DT-ET and operates track instrument R3. As a matter of fact, for trains operating at a speed less than the assumed minimum speed, the highway crossing signals are set into operation in response to operation of the track instrument R3.

Relay BSR functions in a manner similar to relay 3SR of Fig. 1. In the case a medium speed train is traveling through the timing sections 45 AT-BT and the relay TPSR has been picked up, and the circuit for the relay CR is interrupted accidentally, the release of relay CR to close back contact CR83 is ineffective to retain relay TPSR energized over its stick circuit, since 50 front contact BSR82 is not closed until after the relay TPSR is released.

Although we have herein shown and described only two forms of apparatus embodying our invention, it is understood that various changes and modifications may be made therein within the scope of the appended claims without departing from the spirit and scope of our invention.

Having thus described our invention, what we claim is:

1. In combination, a stretch of railway track intersected by a highway, a highway crossing signal located at the intersection; time measuring means including a control relay, a slow pickup relay and a slow release relay; a first, a second, and a third track section to one side of the highway; a track circuit for each section including a track relay, a repeater relay for the track relay of the second section, a first pickup circuit for the control relay including a back contact of the track relay for the first section and a front contact of the track relay for the second section, an operating circuit for the slow pickup relay including a front contact of the control relay, a pickup circuit for the slow release relay including a front contact of the

slow pickup relay, a stick circuit for the slow release relay including a back contact of the track relay of the second section and a front contact of said repeater relay, a second pickup circuit for the control relay including a front contact of the slow release relay and a back contact of said repeater relay as well as a front contact of the track relay of the third section, and circuit means for governing the operation of said signal including a front contact of the control relay and a front contact of the slow release relay in multiple.

2. In combination, a stretch of railway track intersected by a highway, a highway crossing signal located at the intersection, two consecutive timing track sections to one side of the highway, a normally energized traffic controlled relay for each section which becomes deenergized in response to a train entering the section, a slow acting repeater relay for the traffic controlled relay of the section nearer the highway; time measuring means including a control relay, a slow pickup relay and a slow release relay; a first energizing circuit for the control relay including a back contact of the traffic controlled relay of the more remote section and a front contact of the traffic controlled relay of the nearer section, an operating circuit for the slow pickup relay including a front contact of the control relay, a pickup circuit for the slow release relay including a front contact of the slow pickup relay, a stick circuit for the slow release relay including a front contact of said repeater relay and a back contact of the traffic controlled relay of the nearer section, a second energizing circuit for the control relay including a back contact of the repeater relay in series with a front contact of the slow release relay and a front contact of the control relay in multiple, and control circuit means for governing the operation of the signal comprising a main path including a front contact of the repeater relay and a branch path including a front contact of said control relay.

3. In combination, a stretch of railway track intersected by a highway, a highway crossing signal located at the intersection, two consecutive timing track sections to one side of the highway, a normally energized traffic controlled relay for each section which becomes deenergized in response to a train entering the section, a slow acting repeater relay for the traffic controlled relay of the section nearer the highway; time measuring means including a control relay, a slow pickup relay and a slow release relay; a first energizing circuit for the control relay including a back contact of the traffic controlled relay of the more remote section and a front contact of the traffic controlled relay of the nearer section, an operating circuit for the slow pickup relay including a front contact of the control relay, a pickup circuit for the slow release relay including a front contact of the slow pickup relay, a stick circuit for the slow release relay including a front contact of said repeater relay and a back contact of the traffic controlled relay of the nearer section, a second energizing circuit for the control relay including a back contact of the repeater relay in series with a front contact of the slow release relay and a front contact of the control relay in multiple, and control circuit means for governing the operation of the signal comprising a main path including a front contact of the repeater relay and two branch paths in multiple one of which includes a front contact of the slow release relay and the other one of which includes a front contact of the control relay.

4. In combination, a stretch of railway track intersected by a highway, a highway crossing signal located at the intersection, two consecutive timing track sections to one side of the highway, a normally energized traffic controlled relay for each section which becomes deenergized in response to a train entering the section, a slow release repeater relay for the traffic controlled relay of the section nearer the highway; a time measuring means including a control relay, a slow acting relay, and a slow release relay; a first energizing circuit for the control relay including a back contact of the traffic controlled relay for the section more remote from the highway and a front contact of the traffic controlled relay for the section nearer the highway, an operating circuit for the slow acting relay including a contact operated by the control relay, a pickup circuit for the slow release relay including a contact operated by the slow acting relay in a predetermined time interval, a stick circuit for the slow release relay including a back contact of the traffic controlled relay for the nearer section and a front contact of the repeater relay, a second energizing circuit for the control relay including a back contact of the repeater relay in series with a front contact of the slow release relay and a front contact of the control relay in multiple, and control circuit means for governing the operation of the signal comprising a main path including a front contact of the repeater relay and a branch path including a front contact of the control relay.

5. In combination, a stretch of railway track intersected by a highway, a highway crossing signal located at the intersection, a timing section and a first and a second operating section arranged in the order named to one side of the highway, a normally energized track relay for each section which becomes deenergized in response to a train entering the section, a time measuring means including a slow acting relay and a stick relay, control means for operating said slow acting relay including a back contact of the track relay of the timing section and a front contact of the track relay of the first operating section, a pickup circuit for the stick relay including a contact operated by the slow acting relay in a predetermined time interval, a stick circuit for said stick relay including a back contact of the track relay of the first operating section, and control circuit means for governing the operation of the signal comprising a main path including a front contact of the track relay of the first operating section and a branch path including a front contact of the stick relay and a front contact of the track relay of the second operating section in series.

6. In combination, a stretch of railway track intersected by a highway, a highway crossing signal located at the intersection; a first, a second, a third, and a fourth track section arranged to one side of the intersection; a normally energized track relay for each track section which becomes deenergized in response to a train entering the section, a slow release repeater relay for the track relay of the second section; a time measuring means including a control relay, a slow pickup relay and a slow release relay; a first energizing circuit for the control relay including a back contact of the track relay of the first section and a front contact of the track relay of the second section, an operating circuit for the slow pickup relay including a front contact of the control relay, a pickup circuit for the slow release relay including a front contact of the slow pickup relay including a front contact of the slow pickup re-

- lay, a first stick circuit for the slow release relay including a back contact of the track relay of the second section and a front contact of the repeater relay, a second energizing circuit for said control relay including a front contact of the slow release relay and a back contact of the repeater relay, a stick circuit for the control relay including a front contact of the track relay of the third section, a second stick circuit for the slow release relay including a back contact of the track relay for the third section and a front contact of the track relay for the fourth section, and control circuit means for governing the operation of said signal comprising a main path including a front contact of the track relay for the second section and two branch paths one of which includes a front contact of the slow release relay and the other of which includes a front contact of the control relay.
7. In combination, a stretch of railway track intersected by a highway, a highway crossing signal located at the intersection, a normally deenergized slow pickup relay, a normally deenergized slow release relay, a control relay; a first, a second, a third, and a fourth track section to one side of the intersection, a track relay for each section which becomes deenergized in response to a train entering the section, means including a back contact of the track relay for the first section to energize the control relay, means including a front contact of the control relay to energize the slow pickup relay, means including a front contact of the slow pickup relay to energize the slow release relay, means controlled by the track relay of the second section and including a front contact of the slow release relay to release and reenergize the control relay for releasing and reenergizing the slow pickup relay in response to a train passing from the first section into the second section, a stick circuit for said slow release relay including a back contact of the track relay for the third section, means including a winding effective when deenergized to operate the signal, a first control circuit to energize said winding including a front contact of the track relay of the second section, and other control means to energize said winding including front contact of the track relay of the fourth section in series with front contacts of the control relay and slow release relay in parallel.
8. In combination, a stretch of railway track intersected by a highway, a highway crossing signal located at the intersection, a first, a second, and a third track section to one side of the intersection, a traffic controlled relay for each section which becomes deenergized in response to a train entering the section, a first slow release relay energized over a front contact of the traffic controlled relay of the second section, a control relay, a slow pickup relay energized over a front contact of the control relay, a second slow release relay energized over a front contact of the slow pickup relay, means including a back contact of the traffic controlled relay of the first section and a front contact of the traffic controlled relay of the second section to energize the control relay to operate the slow pickup relay and energize the second slow release relay when a train occupies the first section for an interval greater than the pickup period of the slow pickup relay, means controlled by the traffic controlled relay of the second section to release the first and second slow release relays in sequence and to release the control relay in response to a train entering the second section, means controlled by

said slow release relays to reenergize the control relay to initiate a second operation of the slow pickup relay to reenergize the second slow release relay when a train occupies the second section for an interval greater than the pickup period of said slow pickup relay, a stick circuit for said second slow release relay including a back contact of the traffic controlled relay for the third section, and means including a front contact of said second slow release relay for governing the operation of the signal.

9. In combination, a stretch of railway track intersected by a highway, a highway crossing signal located at the intersection; a first, a second, and a third track section to one side of the intersection, a traffic controlled relay for each section which becomes deenergized in response to a train entering the section, a first slow release relay energized over a front contact of the traffic controlled relay of the second section, an electro-responsive time measuring device including a check contact closed only in the normal position of said device, a second slow release relay energized over a contact of said device closed only after the device is energized a predetermined time period, means controlled over a back contact of the traffic controlled relay of the first section to energize said device to pick up the second slow release relay when a train occupies the first section for an interval greater than said time period, means controlled by the traffic controlled relay of the second section to release the first and second slow release relays in sequence and to deenergize said device in response to a train entering the second section, means controlled by said slow release relays and including said check contact to initiate a second energization of the time measuring device to again pick up the second slow release relay when a train occupies the second section for an interval greater than said time period, a stick circuit for said second slow release relay including a back contact of the traffic controlled relay of the third section, and means including a front contact of the second slow release relay for governing the operation of the signal.

10. In combination, a first and a second consecutive track section, a normally energized traffic controlled relay for each section which becomes deenergized when a train enters the section, a normally deenergized slow pickup relay, circuit means for energizing the slow pickup relay and including a back contact of the traffic controlled relay of the first section and a front contact of the traffic controlled relay of the second section, a stick circuit for the slow pickup relay including a back contact of the traffic controlled relay of the second section, a slow release stick relay, time measuring means controlled over a back contact of the traffic controlled relay of the first section and a front contact of traffic controlled relay of the second section effective to energize said slow release relay when operated a predetermined time interval, a stick circuit for said slow release relay including a back contact of the traffic controlled relay of the second section and a front contact of the slow pickup relay, and signal control means including a front contact of said slow release relay.

11. In combination; a stretch of railway track formed into a first, a second, and a third consecutive track section; a normally energized traffic controlled relay for each section which becomes deenergized when a train enters the section, time measuring means including a stick relay which

- becomes energized a predetermined time interval after said time measuring means is set into operation, means including a back contact of the traffic controlled relay of the first section and a front contact of the traffic controlled relay of the second section to set the time measuring means into operation, a signal, control means including a front contact of the traffic controlled relay of the third section for governing the operation of the 5 signal, means including a front contact of said stick relay to render said control means ineffective to govern the operation of the signal, a stick circuit for the stick relay including a back contact of the traffic controlled relay of the third section, a normally deenergized slow pickup relay, 10 a pickup circuit for the slow pickup relay including a back contact of the traffic controlled relay of the second section and a front contact of the traffic controlled relay of the third section, a stick circuit for said slow pickup relay including a back contact of the traffic controlled relay of the third section, and a front contact of said slow pickup relay interposed in said stick circuit of the stick 15 relay whereby accidental deenergizing of the traffic controlled relay of the third section is ineffective to retain the stick relay picked up.
12. In combination, a stretch of railway track intersected by a highway, a highway crossing signal located at the intersection; a first, a second, and a third track section to one side of the intersection, a normally energized track relay for each section which becomes deenergized when a train enters the section, time measuring means 20 including a contact which becomes closed a predetermined time interval after said measuring means becomes energized, means including a back contact of the track relay of the first section to energize the measuring means to close its contact when a train consumes more than said time interval in advancing through the first section, control means including a front contact of each of the track relays of the second and third sections for operating said signal, means including 25 the contact of said measuring means when closed to render said control means ineffective to operate the signal, stick circuit means including a back contact of the track relay of the third section effective to retain the contact of said measuring means closed, a slow pickup relay, a pickup circuit for said slow pickup relay including a back contact of the track relay of the second section and a front contact of the track relay of the third section, and a front contact of said 30 slow pickup relay interposed in said stick circuit means whereby deenergization of the track relay of the third section while a train is approaching in either the first or the second section annuls the control of the time measuring means over the signal.
13. In combination, a stretch of railway track which is formed into a single insulated track section, a track circuit including a track relay for the section, a highway intersecting said section adjacent the exit end, a highway crossing signal located at the intersection, three track instruments located at selected points to cooperate with the track circuit to form said insulated track section into four control track sections, a traffic controlled relay associated with each track instru- 35
- ment which becomes deenergized in response to a train passing the instrument and becomes energized when the track relay of the insulated track section is picked up, a single electroresponsive time measuring means, circuit means controlled by said track relay and said traffic controlled relay to associate successively the time measuring means with the first and second control track sections encountered in approaching the highway, operating means controlled by the traffic controlled relays of the second and third control track sections to operate the signal, means controlled by the time measuring means to render at times said operating means ineffective to operate the signal, and means controlled by the traffic controlled relay of the final control track section encountered in approaching the highway to cause said operating means to operate the signal irrespective of the time measuring means. 40
14. In combination, a stretch of railway track formed into a single insulated track section which is intersected by a highway at its exit end, a track circuit for said section including a track relay, a highway crossing signal at the intersection; a first, a second and a third track instrument placed at selected locations to cooperate with the track circuit to form said section into four consecutive control sections; said instruments each including a contact adapted to be actuated by a train, an electroresponsive time measuring means, circuit means controlled jointly by said track relay and said first track instrument to associate successively the time measuring means with the first and second control sections encountered by a train approaching the highway, operating means controlled by the first and second track instrument to operate the signal, means controlled by the time measuring means to render at times said operating means ineffective to operate the signal, and other means controlled by the third track instrument to cause said operating means to operate the signal. 45
15. In combination, a stretch of railway track intersected by a highway, a highway crossing signal located at the intersection, three track instruments placed at selected locations to one side of the intersection, a time measuring means having a predetermined operating period, circuit means controlled by a train approaching the most remote instrument to operate the time measuring means, other circuit means governed by the most remote instrument to reset and initiate a second operation of the time measuring means in response to the train reaching the location of that instrument, means controlled by the next instrument encountered by the train to stop the operation of the time measuring means, operating means governed by the most remote instrument and by the next instrument encountered by the train to operate the signal, means governed by the time measuring means when it has completed its operation to render said operating means ineffective to operate the signal, and other means controlled by the track instrument nearest to the intersection to cause said operating means to operate the signal. 50
